UNITED STATES PATENT OFFICE.

DAVID SARASON, OF BERLIN, GERMANY.

HEAD-REST FOR CHAIRS.

No. 845,822.

Specification of Letters Patent.

Patented March 5, 1907.

Application filed February 15, 1905. Serial No. 245,805.

To all whom it may concern:

Be it known that I, DAVID SARASON, a subject of the King of Prussia, German Emperor, residing in Berlin, in the Kingdom of Prussia, 5 German Empire, have invented new and useful Improvements in Head-Rests for Chairs, of which the following is a specification.

The subject of my invention is an improved pad made of sheets of soft paper of suitable size and fitted with attachment means of appropriate form and dimensions for application to the back or head-rest of surgeons', dentists', or hairdressers' chairs in 15 order to present a clean and hygienic surface on each occasion of use.

My invention is illustrated in the accompanying drawing, in which—

Figure 1 shows the new pad alone, and Fig. 20 2 shows it applied to a chair.

a is a pad consisting of a plurality of superposed sheets of stout tissue-paper perforated laterally at d.

b is an elastic band passed through the 25 holes d and retained therein by means of buttons c. In order to attach the pad to the head-rest of an operating-chair A, it is merely necessary to pass the band around the same.

It will be obvious that instead of an elastic 30 band any other suitable elastic attachment means extending from one end of the pad to

the other may be employed, and naturally more than a single band b or like member may be used, if desired.

The studs or buttons c may likewise be of 35 any suitable character, whether of round or oval, plate, or bar pattern. Instead of such, hooks or clips or any other appropriate devices may be employed.

Having thus described my invention, what 40 I claim as new, and desire to protect by Letters Patent, is—

A pad for the head-rests of chairs or the like, comprising a plurality of superposed sheets of paper, having oppositely-disposed 45 perforations near the ends thereof, the respective perforations at each end, registering, whereby a pad having oppositely-disposed openings is formed, and attaching means extending through the openings in said pad and 50 holding said sheets together, said attaching means also extending from one opening to another, whereby the pad is adapted to be attached to the head-rest.

In witness whereof I have hereunto signed 55 my name, this 1st day of February, 1905, in the presence of two subscribing witnesses.

DAVID SARASON.
